UNITED STATES PATENT OFFICE.

RODRICK C. CUMMINGS, OF MALONE, NEW YORK.

CATTLE-GUARD.

SPECIFICATION forming part of Letters Patent No. 630,329, dated August 8, 1899.

Application filed May 4, 1899. Serial No. 715,577. (No model.)

To all whom it may concern:

Be it known that I, RODRICK C. CUMMINGS, a citizen of the United States, residing at Malone, in the county of Franklin and State of New York, have invented certain new and useful Improvements in Cattle-Guards; and I do hereby declare the following to be a full, clear, and exact description of the invention, such as will enable others skilled in the art to which it appertains to make and use the same.

This invention relates to cattle-guards for railways of the class which are actuated by the weight of the animal when stepping upon a platform to which the guard is pivotally attached, said guard normally folding, so as not to obstruct the track or interfere with the free movement of trains.

The invention will appear and be more fully set forth hereinafter, and to this end and to a full disclosure of the merits and advantages of the same reference is to be had to the following description and the views of the drawings hereto attached.

While the preferred embodiment of the invention is illustrated, it is to be understood that under certain conditions various changes in the form, proportion, and minor details of construction may be resorted to without departing from the nature or sacrificing any of the advantages of the invention.

In the drawings, Figure 1 is a top plan view of a section of railway, showing the invention operatively applied. Fig. 2 is a perspective view of the guard as it will appear when actuated and obstructing the passage of the animal from one inclosure to another. Fig. 3 is a longitudinal section on the line X X of Fig. 1, the guard being folded. Fig. 4 is a view similar to Fig. 3, the guard being elevated. Fig. 5 is a front view of the bail and its supports. Fig. 6 is a front view of the arched frame or standard.

Corresponding and like parts are referred to in the following description and indicated in all the views of the drawings by the same reference characters.

The invention in common with like appliances is designed to prevent the passage of cattle from one field or inclosure to another or into the inclosure of the railway. At the gap or break in the line of fencing through which the railway passes the guard is located

and consists of three parts or separate and independent guards, one arranged between the rails of the track and the other two at the sides of the track and between the latter and the ends of the fencing. Inasmuch as the guards are alike in construction, a detail description of one only will be given.

A bail 1 is composed of a horizontal portion 2 and vertical arms 3, which are pivotally connected at their upper ends to standards or supports 4 adjacent to the rails of the track and secured at their lower ends to a tie thereof. The bail is preferably formed of a rod or bar having its end portions formed into eyes which receive journals 5, projecting laterally from the upper ends of the standards 4. An arched frame or standard 6 is secured to a tie of the railway and is located a distance from the bail, and its horizontal portion 7 forms a support for the guard 8, which is mounted to turn thereon.

The guard 8 may be of any suitable construction, and as shown is composed of side bars 9, crossed braces 10, and an end bar 11, the parts being firmly joined at their overlapping ends by means of bolts, rivets, or other like fastenings. The side bars 9 are extended in the rear of the arched frame or standard 6 and are hinged or pivoted to the rear end of the platform 12. Staples or U-shaped clips 13 are applied to the side bars of the guard and receive the horizontal portion 7 of the frame 6 and connect said guard with the said frame.

The platform 12 is loosely supported at its front end upon the horizontal portion 2 of the bail 1, and its rear end is hingedly connected to the rear end of the guard 8 about as set forth or in any convenient and substantial manner. A transverse groove 14 is formed in the top side of the platform, near its rear end, and receives the horizontal portion 7 of the frame 6, longitudinal depressions 15, intersecting the end portions of the transverse grooves, receiving the U-shaped clips or staples 13, thereby permitting the guard to fold close against the top side of the platform. A fender or strip 16 is attached to the top side of the platform 12 and is inclined forwardly and downwardly and is disposed so as to extend in front of the guard 8 when the latter is folded, thereby preventing any obstacle

from lodging against the forward end of the guard.

The middle guard is located between the rails of the track, and its edges are spaced about two inches therefrom, so as to provide ample clearance for the wheels of a passing car or train. The guard is proportioned and arranged so as to occupy a position below the plate of the rails, so as to be normally out of the way. The side guards are similarly disposed, and their inner edges are spaced from the rails a proper distance, so as not to obstruct or interfere with the wheels of a passing train. These side guards occupy the space between the extremities of the fencing and the rails of the track. As previously stated, the guard normally occupies a folded position. In the event of animals attempting to pass from one inclosure to another or upon the railway the weight of the animal when stepping upon the platform 12 will be sufficient to lower or cause the descent of the rear end of said platform and the corresponding end of the guard pivoted thereto, and as the rear end of the guard is depressed its forward end will be correspondingly elevated by reason of the guard turning upon the horizontal portion 7 of the arched frame or standard 6. When the platform is depressed, the guard will assume the position about as shown in Fig. 2 and will obstruct and prevent the further advance of the animal. As the animal steps from the platform the latter and the guard will assume a normal position by reason of the weight of the guard in advance of its axial or pivotal line. The parts are disposed so as to prevent the guard from assuming a vertical position. Hence the preponderance of weight of the guard is in advance of the horizontal portion 7 and normally exerts a pressure or force to hold the parts in a normal or given position.

The platform is considerably longer than the guard, being about double the length, and is disposed with the projecting end portion in front of the free end of the guard, so

that an animal stepping upon the front end of the platform will cause the guard to swing upwardly and rearwardly and prevent the animal from advancing thereon and pressing it down upon the platform, which would be the case if the guard were disposed to swing upward and forward, with the free end facing away from the approach instead of toward it, as in the present instance. 55

Having thus described the invention, what is claimed as new is—

1. In a cattle-guard, the combination with a guard pivotally supported a distance from its rear end and normally folded, of a platform having hinged or pivotal connection at its rear end with the rear end of the guard and normally elevated thereby, and a fender or strip secured to the top side of the platform for the front end of the guard to fold 60 behind, as and for the purpose set forth. 65

2. A cattle-guard, comprising standards having lateral journals, a bail suspended from said journals, an arched frame located at a distance from said standards, a guard mounted to turn upon the horizontal portion of the arched frame and adapted to swing upward and rearward at its free end, clips connecting the guard with the said frame, and a platform loosely supported at its front end upon the horizontal portion of the bail and having its rear end pivoted or hinged to the rear end of the guard in the rear of the horizontal portion of the said arched frame, and having a transverse seat to receive the horizontal portion of the frame, and intersecting depressions to receive the clips, said platform having its front portion extending in advance of the free end of the guard when the latter is folded, substantially as specified. 70 75 80

In testimony whereof I affix my signature in presence of two witnesses. 85
